UNITED STATES PATENT OFFICE.

MARION F. BENCH, OF CHILlicothe, Missouri, AND OTTO F. ROHWEDDER, OF DAVENPORT, IOWA.

DISPLAY RACK.

Application filed March 19, 1925. Serial No 16,761.

Our invention relates to improvements in display racks and has reference more particularly to one which is designed primarily for use in displaying loaves of bread.

5 It is the object of the invention to provide an extremely simple and inexpensive device of the class set forth which will effect a very attractive display and will act also as a storage device in which a number of 10 other loaves of bread may be placed, independently of those on display, so that whenever a loaf is sold, the loaves in view of the customers need not be removed from the rack.

15 With the foregoing in view, the invention resides in the novel subject matter hereinafter described and claimed, the description being supplemented by the accompanying drawing.

20 Figure 1 is a rear elevation.

Figure 2 is a top plan view.

Figure 3 is an end view.

Figure 4 is a vertical transverse section as indicated by line 4—4 of Fig. 2.

25 Figure 5 is a vertical longitudinal sectional view as indicated by line 5—5 of Fig. 4.

In the drawing above briefly described, the numeral 1 designates a rectangular bottom

30 which is preferably formed of sheet metal, a portion of said bottom being preferably bent upwardly to provide a front wall 2 which is of infinitesimal height with respect to a pair of end walls 3 which rise from the bottom. These end walls are of ornamental shape and preferably formed with beaded edges 4, and to secure them in place, we prefer- 35

40 ed to bend their lower edges horizontally to provide flanges 5 which are secured against the lower side of the bottom 1 by bolts or other appropriate fasteners 6. The end walls 3 are also preferably formed with additional inwardly bent flanges 7 which are disposed vertically and secured to the inner 45

side of the front wall 2 by bolts or the like 8.

Extending between the intermediate portions of the end walls 3, is a shelf 9 which preferably declines forwardly, said shelf being disposed at an elevation above the front 50 wall 2 and being spaced rearwardly from this wall, providing a space in which loaves of bread or other articles may stand, as indicated by the dotted lines 10 in Figs. 2 and 4.

55 In the construction shown, the front portion of the shelf 9 is bent downwardly to

form a vertical flange 11 which constitutes a barrier wall between the shelf and the bottom 1, against which the rear sides of the articles 10 may rest, so as to hold them against rearward displacement. This barrier wall preferably terminates a distance 60 from the bottom 1, greater than the thickness or width of a loaf of bread. Thus, the loaves of bread 10 may be forwardly inserted from the rear of the rack, under said 65 barrier wall, and angled to dispose them in upright position. The ends of the shelf 9 and its flange 11 are preferably bent laterally to provide vertical flanges 12 secured to the end walls 3 by bolts or the like 13, so 70 as to not only support the shelf and flange 11, but to relatively brace said end walls.

The shelf 9 preferably declines forwardly, and to prevent the loaves of bread or other articles placed thereon, from sliding forwardly from said shelf, we have shown a vertical plate 14 secured to the barrier wall 11 and projecting above the shelf to constitute a ledge for engagement with such articles, the latter being indicated at 15 in 80 Figs. 2 and 4.

The rear of the rack is open so that the space under the shelf 9 and in rear of the barrier wall 11, may be utilized for the storage of loaves of bread or other articles. 85 Thus, whenever a sale is made, one of the articles may be removed from the storage space, without the necessity of taking an article from the front portion of the rack or the shelf 9. Thus, the display is not in- 90 terfered with.

The primary use of the invention is in retail stores and it may well be furnished to the merchants by the bakeries supplying them with bread. In exchange for this 95 courtesy, the merchants may well display a distinct advertisement for the baker or bakers, for which purpose, display openings 16 are provided in the lower portions of the end walls 3, said end walls having appropriate means 17 at the upper and lower edges of these openings, to hold advertising cards 18 in place, so that they will be visible through said openings. In the device as manufactured, the major portion of each 100 end wall 3, preferably displays an attractive illustration, for instance, a picture of a person eating and obviously enjoying bread of the kind displayed by the rack.

Excellent results are obtainable from the 110

details disclosed and such details are therefore by preference followed. However, within the scope of the invention as claimed, modifications may of course be made.

5 We claim:

1. A rack for displaying and storing loaves of bread, comprising a bottom, a pair of vertical end walls rising therefrom, a front wall at right angles to said bottom and rising from the latter a distance less than the length of a loaf of bread, said front wall extending from one of said end walls to the other, a forwardly declined shelf extending between and secured at its ends to said end walls at a distance above said bottom greater than the length of a loaf of bread, and a barrier wall projecting downwardly from the front edge of said shelf at right angles to said bottom and extending from one of said end walls to the other, said barrier wall being spaced rearwardly from the plane of said front wall a distance corresponding to the thickness of a loaf of bread, said barrier wall extending downwardly from the shelf to an extent to lie against the loaves of bread standing on end between said front wall and said barrier wall, the rear of the rack being open to permit the storage of other loaves of bread beneath the shelf.
- 20 2. A rack for displaying and storing loaves of bread comprising a bottom, a pair

of vertical end walls rising therefrom, a front wall at right angles to said bottom and rising from the latter a distance less than the length of a loaf of bread, said front wall extending from one of said end walls to the other, a forwardly declined shelf extending between and secured at its ends to said end walls at a distance above said bottom greater than the length of a loaf of bread, and a barrier wall projecting downwardly from the front edge of said shelf at right angles to said bottom and extending from one of said end walls to the other, said barrier wall being spaced rearwardly from the plane of said front wall a distance corresponding to the thickness of a loaf of bread, said barrier wall extending downwardly from the shelf to an extent to lie against the loaves of bread standing on end between said front wall and said barrier wall, but terminating a distance from the bottom considerably greater than the thickness or width of a loaf of bread, permitting forward passage under said barrier wall of the loaves which are to be stood on end, the rear of the rack being open to permit the storage of other loaves of bread beneath the shelf.

55 In testimony whereof we have hereunto affixed our signatures.
